UNITED STATES PATENT OFFICE.

JOSEPH STUMPF, OF AUSTIN, TEXAS.

WAGON-BODY.

SPECIFICATION forming part of Letters Patent No. 372,775, dated November 8, 1887.

Application filed July 15, 1887. Serial No. 244,403. (No model.)

To all whom it may concern:

Be it known that I, JOSEPH STUMPF, a citizen of the United States, residing at Austin, in the county of Travis and State of Texas, have invented a new and useful Improvement in Extensible Wagon-Bodies, of which the following is a specification.

My invention relates to an improvement in extensible wagon-bodies; and it consists in the construction and arrangement of the parts of the same, which will be more fully hereinafter described, and clearly pointed out in the claims.

In the accompanying drawings, wherein like letters of reference indicate similar parts in the several views, Figure 1 is a perspective view of my improved extensible wagon-body. Fig. 2 is a bottom plan view of the said body, shown extended to its full length. Fig. 3 is a perspective view of the two portions of the body, shown disconnected. Fig. 4 is an end elevation of one-half of the body. Fig. 5 is a detail perspective view of one of the strap-bolts used in connection with my improvement.

A A indicate the bottom frame or sills of the inside front body, and B B the frame or sills of the outside or rear body.

C C represent cross-sills bolted to the front body and extending beyond the sills B B, and provided with the lip irons or plates K K on their ends, for purposes which will be more fully hereinafter set forth. The lip irons or plates K K and the cross-sills or bars C C have a hole, e, formed therethrough, which is adapted to be engaged by a pin or thumb-screw, e', for fastening the sills B B to the front cross-sill C when in a normal position, or to the rear sill C when extended.

D is a crank-shaft having a toothed or sprocket wheel, E, mounted in connection with the central portion, and with handles or cranks G G, which may either be made integrally with the shaft D or with sockets, so as to be removed, or a common wrench can be used in their stead, if so desired.

H H represent two hanger journal-boxes, which are bolted to the side sills, B B, and in which the crank-shaft D is journaled.

F indicates a square linked or jointed chain of the usual form of chain belt, which is secured at one of its ends to the cross-sill C, and passes over and in contact with the bracket-

wheel E, and at its other end is secured to the end sill C.

The crank-shaft being journaled to the outside body and the chain being fastened to the inside body, the bodies are readily shoved out or pulled together, as desired, by the wheel E engaging the chain F when the crank-shaft is turned by the operator.

It will be seen that the bottom boards, S, 60 cover the entire body of the front body portion and run crosswise, as shown, while only one-half of the rear body is floored by the boards e, which run lengthwise, the said boards e being arranged lower than the boards S, and 65 thus pass under the latter when the body is drawn together.

In order that the parts may readily slide one upon the other, openings w are formed in the rear portion of the rear body, which are 70 adapted to be closed by the sliding panels W W, secured on the underside of the said body.

T represents the side panels, which are screwed to the sills A in the well-known manner, and have the rail R secured on their top 75 edges, which acts as a flange, and, in conjunction with the strap-bolts m and the lip-irons K, a way is formed in which the rear body slides when the two bodies are united, as hereinafore set forth.

In building this wagon the back gear is always fastened to the outside or rear body, while the front gear is fastened to the front or inside body. If platform-gear is used, it will be readily seen that no change in mounting 85 thereof will be necessary; but if three-spring or other gear with a reach is used it will be necessary to make the gear in such a manner as not to interfere with the operation of the wagon-body.

The novelty and utility of my improved device being obviously apparent and appreciable, it is unnecessary to further enlarge upon the same herein.

I also propose to make the wagon-body, as 95 herein described, of sheet-iron or other analogous material which will combine strength and lightness in weight.

Having thus described my invention, what I claim is—

1. In an extensible wagon-body, the combination of two sets of sills, A B, the cross-sills

C, the panels T, the lip-irons K, the top rail, R, and the strap-bolts *m*, substantially as described.

2. In a wagon-body, the combination of the shaft D, the hanger journal-boxes H, the chain F, the sprocket-wheel E, and the forward and rearward telescoping body portions, substantially as described.

3. In a wagon-body, the combination, with the rear cross-sill C, one of the lip-plates K, and the outside sills, B, of the thumb-screw *c'*, substantially as described.

4. The combination, with the telescoping body portions, of the transverse boards S, secured to the inner body, the longitudinal boards *e*, secured to the outer body, and the panels W, held to and sliding beneath the boards *e*, substantially as described.

5. The combination, with the telescoping body portions, of the chain F, connected to each of said body portions, the shaft D, and the sprocket-wheel E, in connection with one of said body portions, substantially as described.

6. The combination, with the telescoping body portions, of the panels T, the rail R, and the strap-bolts *m*, substantially as described.

7. The combination, with the rear body portion, of the sliding panels W, substantially as described.

In testimony that I claim the foregoing as my own I have hereto affixed my signature in presence of two witnesses.

JOSEPH STUMPF.
